UNITED STATES PATENT OFFICE.

JOHN HIGHAM, OF LOS ANGELES, CALIFORNIA, ASSIGNOR TO ARTHUR C. HIGHAM, OF LOS ANGELES, CALIFORNIA.

FOLDING STOVE.

Application filed November 4, 1924. Serial No. 747,793.

To all whom it may concern:

Be it known that I, JOHN HIGHAM, a citizen of the United States, residing at Los Angeles, California, in the county of 5 Los Angeles and State of California, have invented new and useful Improvements in Folding Stoves, of which the following is a specification.

This invention particularly pertains to a 10 camp stove of the type adapted to be operated with liquid fuel, and specially relates to a fuel container and the manner of its mounting on the stove.

An object of the invention is to provide 15 a camp stove of the portable type embodying a box-like housing containing a burner and fitted with a fuel reservoir, in which the fuel feed connections between the reservoir and burner are fixed and in which 20 the burner and reservoir are so mounted that the reservoir may be disposed either interiorly or exteriorly of the housing so that the burner and reservoir may be enclosed within the housing when the stove 25 is not in operation, and whereby the fuel reservoir may be disposed on the outside of the housing and shielded from the burner without disconnecting the fuel feed connections from either the reservoir or burner.

Another object is to provide a camp stove 30 embodying the features above specified and including with the main fuel feed connection between the reservoir and burner, an independent secondary fuel feed connection to be employed in delivering of fuel 35 to the burner for effecting initial heating of a vapor generator.

With the foregoing objects in view, together with such other objects and advantages as may subsequently appear, the invention resides in the parts and in the combination, construction and arrangement of parts hereinafter described and claimed and illustrated by the way of example in the 45 accompanying drawings, in which:

Figure 1 is a perspective view of the camp stove with parts broken away.

Figure 2 is a view of the stove housing as seen in rear elevation.

Figure 3 is a view in transverse vertical section of the stove illustrating the burner and reservoir as disposed in their closed position in the stove housing.

Figure 4 is a view in transverse section 55 illustrating the burner and reservoir as dis-

posed to position the reservoir exteriorly of the housing.

Figure 5 is a detail in perspective illustrating the apertured end portion of a removable panel for closing an opening in the 60 rear wall of the housing.

More specifically, 7 indicates a box-like 65 housing having a bottom wall 8, and up-standing front and back walls 9 and 10 and end walls 11 and 12, forming a rectangular enclosure adapted to be closed by a cover 70 panel 13 hingedly connected to the back wall 10. The back wall 10 is formed with an elongated opening 14, extending longitudinally thereof with its lower margin 75 bordered by the bottom wall 8 and with its upper and end margins spaced from the upper edge and ends respectively of the back wall; there being an open ended horizontal slot 15 leading from the end margin 75 of the opening 14 adjacent the end wall 11. The end walls 11 and 12 are formed with elongated horizontally extending slots 16 and 17, respectively.

Arranged in the housing is a vapor generator 80 18 of suitable construction, here shown as embodying a pair of burner heads 19 and 20 carried by a manifold 21 and including a vapor intake throat 22 located between the burner heads 19 and 20. This burner 85 is designed to be slidable on the bottom wall 8 of the housing and for which purpose is here shown as fixed to a pair of spaced slide-bars 23 and 24, slidably transversely of the housing and held in place on the 90 bottom wall 8 by straps 25 constituting guideways; the slide bars having end portions projecting on the opposite sides of the guideways and the burner being carried on the inner end portions thereof. Rigidly 95 mounted on the outer end portions of the slide-bars is a fuel reservoir 26 adapted to contain a liquid fuel under pressure. This reservoir is here shown in the form of a horizontally extending elongated cylinder 100 and is adapted to be moved inwardly and outwardly through the opening 14 in the back wall 10 of the housing so that it may be positioned either interiorly or exteriorly of the housing. The burner and the reservoir are rigidly connected together by the slide-bars and are spaced such distance apart that when the reservoir is positioned 105 interiorly of the housing as shown in Figure 3, the reservoir and burner will be posi-

110

tioned close to the front and back walls of the housing. Leading from the end of the reservoir facing the housing end wall 11, is a fuel feed conduit 27 which is bent to 5 extend along the inner face of the housing end wall 11 and connects with a needle valve casing 28 connecting with a vapor generator 29 extending over the burner head 19 and communicating with the vapor in- 10 take throat 22 of the manifold 21; the feed pipe 27 and its connections being normally arranged wholly within the burner housing and being permanently attached to the reservoir and burner except that it may be 15 detached should occasion require. The needle valve housing 28 is fitted with a needle valve having a handle 30 which projects through the slot 16 to position the handle exteriorly of the housing. The 20 open ended slot 15 in the rear wall 10 of the housing is arranged to permit the feed pipe 27 to pass through the wall 10 on shifting the reservoir.

The burner head 20 is fitted with a control 25 valve having a stem 31 which extends through the slot 17 in the housing end wall 12 and has a handle 32 located exteriorly of the housing. The slots 16 and 30 17 through which the valve stems 30 and 31 extend serve to accomodate movement of the stems as they are carried with the burner and reservoir when moving the latter transversely of the housing. Leading from the reservoir to the burner head 19 is 35 a secondary fuel feed pipe 33 fitted with a cut-off valve 34, which feed pipe opens above a generating pan 35 on the burner head, whereby on opening the valve 34 a supply of fuel will be delivered to the pan 40 35 which fuel on being ignited will serve to initially heat the vapor generator 29.

Means are provided for closing the opening 14 in the back wall 10 whether the reservoir is disposed interiorly or exteriorly 45 of the housing. This means is here shown as comprising a removable panel 36 of sheet metal substantially corresponding in size to the internal dimensions of the back wall 10 and which removable panel is 50 adapted to be placed over the opening 14 from the inside of the housing between the reservoir 26 and the back wall 10, as shown in Figure 3; the panel being held in place by the reservoir and also by means of 55 brackets 37 and 38 mounted on the end walls 11 and 12 and spaced a short distance from the inner face of the back wall 10 to form guideways to receive the end portions of the panel 36.

60 The panel 36 is provided with an horizontal open ended slot 39 at one end thereof and is also formed with an open ended vertically extending slot 40 leading from its lower edge, which slots are provided to 65 accommodate the fuel feed pipes 27 and 33

when the closure panel 36 is set in place to close the opening 14 with the reservoir 26 disposed exteriorly of the housing, as shown in Figure 4.

The upper portion of the housing is fitted 70 with a removal grid 41 which is adapted to seat on the brackets 37 and 38 and on 42 and 43 carried on the front wall 2.

When the stove is not in use, as in transporting or storing same, the burner and 75 reservoir are positioned within the housing as shown in Figure 3, and the closure panel 36 is set in place over the apertured back wall 10 and the cover panel 13 is closed. When it is desired to place the stove in operation the cover panel 13 is raised, the closure panel 36 is removed and the reservoir 26 together with the burner is shifted transversely of the housing to pass the reservoir 80 through the apertured back wall 10 and dispose it exteriorly of the housing; the burner then being moved to a more central position in the housing. The closure panel 36 is then set in place so as to close the opening 14 and form a wall or shield between the 85 burner and the reservoir whereby the latter is protected from heat and flames generated at the burners.

I claim:—

1. In a camp stove, a box-like housing, a 90 fuel reservoir slidably carried by said housing and adapted to be positioned either interiorly or exteriorly thereof, a burner arranged in said housing connected to said reservoir, and a fuel feed conduit fixedly connected to said reservoir and burner. 100

2. In a camp stove, a box-like housing, a reservoir slidably carried by said housing and adapted to be positioned either interiorly or exteriorly thereof, a burner arranged in said housing connected to said reservoir to slide therewith, and fuel feed connections between said reservoir and burner. 105

3. In a camp stove, a box-like housing, a reservoir slidably carried by said housing and adapted to be positioned either interiorly or exteriorly thereof, a burner connected to said reservoir in spaced relation thereto, adapted to slide therewith, and a movable panel adapted to be interposed between said reservoir and burner when the reservoir is positioned exteriorly of the housing. 110

4. In a camp stove, a substantially box-like housing having a bottom wall and an upstanding wall along the margin of said bottom wall, said upstanding wall being formed with an elongated opening, a fuel reservoir slidably carried on said housing adapted to be positioned within said housing and to be moved through said opening to a position exteriorly of the housing, a burner slidably carried in said housing and connected to said reservoir in spaced relation 115 120 125 130

thereto and adapted to slide therewith, and movable panel adapted to close the opening in the upstanding wall when the reservoir is positioned either interiorly or exteriorly of the housing.

5. In a camp stove, a substantially box-like housing embodying a bottom wall and an upstanding wall along the margin of said bottom wall having an opening 10 therein, a slide bar carried by said bottom wall, a fuel reservoir carried by said slide bar, a burner carried by said slide bar, a fuel delivery connection between said reservoir and burner, said slide being operable 15 to dispose said reservoir either interiorly or exteriorly of the housing through said opening, and means for closing said opening.

6. In a camp stove, a box-like housing 20 having bottom, side and end walls, there being an opening in one of the side walls and a slot in one of the end walls, a slidable member mounted in said housing, a fuel reservoir carried by said slidable member

adapted to be positioned either interiorly or exteriorly of said housing through said opening, a burner mounted on said slidable member, a fuel feed pipe leading from said reservoir to said burner, and a valve in said fuel pipe having an operating handle extending through the slot in the housing end wall.

7. In a camp stove, a box-like housing having a side opening, a fuel reservoir, a slide bar mounted in said housing carrying said reservoir, adapted to be shifted to dispose the reservoir either interiorly or exteriorly of the housing through said opening, a burner carried by said slide bar and movable therewith in spaced relation to said reservoir, a fuel conduit fixedly connecting said reservoir and burner, a valve in said conduit having a handle arranged exteriorly of said housing, and means for closing the side opening in said housing with the reservoir 40 disposed either interiorly or exteriorly of the housing.

JOHN HIGHAM.
